(57) **CLAIM**

The ornamental design for a computer generated image for display panel or screen, as shown and described.

DESCRIPTION

FIG. 1 is a front elevational view of a first embodiment of a computer generated image for a display panel or screen showing our new design;

FIG. 2 is a front elevational view of a second embodiment of a computer generated image for a display panel or screen showing our new design;

FIG. 3 is a front elevational view of a third embodiment of a computer generated image for a display panel or screen showing our new design;

FIG. 4 is a front elevational view of a fourth embodiment of a computer generated image for a display panel or screen showing our new design; and,

FIG. 5 is a front elevational view of a fifth embodiment of a computer generated image for a display panel or screen showing our new design.

The dot-dash broken lines in FIGS. 1-5 define the bounds of the claimed design and form no part thereof.
